CLAIM

The ornamental design for a dual pet leash handle, as shown and described.

DESCRIPTION

FIG. 1 is a right front perspective view of a dual pet leash handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The structural elements depicted by broken lines in the drawings have been shown for the purpose of illustrating portions of the dual pet leash handle that form no part of the claimed design.

1 Claim, 5 Drawing Sheets(56)
